UNITED STATES PATENT OFFICE.

CLARENCE G. CASHMAN, OF WAYNESBORO, PENNSYLVANIA, ASSIGNOR OF ONE-HALF
TO JOHN B. EADER, OF WAYNESBORO, PENNSYLVANIA.

LATHE-DOG.

1,368,485.

Specification of Letters Patent. Patented Feb. 15, 1921.

Application filed November 17, 1919. Serial No. 338,647.

To all whom it may concern:

Be it known that I, CLARENCE G. CASHMAN, a citizen of the United States, residing at Waynesboro, in the county of Franklin 5 and State of Pennsylvania, have invented certain new and useful Improvements in Lathe-Dogs, of which the following is a specification.

This invention relates to lathe dogs, and 10 has for an object to provide a dog which is secured in and carried by the tool-holder of an ordinary lathe, and adapted to hold a drill, bit, or other boring implement, against rotation while the work is being rotated by 15 the head, and to compensate for movements of the drill and also the vertical position of the drill relative to the tool-holder.

With these and other objects in view, the 20 invention comprises certain novel combinations and arrangements of parts as will be hereinafter more fully described and claimed.

In the drawings,

Figure 1 is a top plan view of a conventional lathe with a dog applied thereto holding a boring implement.

Fig. 2 is a perspective view of one type of the dog.

Fig. 3 is a view of a dog in edge elevation. 30 Fig. 4 is a longitudinal, sectional view of the improved dog.

Fig. 5 is a sectional view of a modified form of a dog.

Fig. 6 is a perspective view of the type of 35 dog shown at Fig. 5.

Like characters of reference indicate corresponding parts throughout the several views.

The improved dog, which forms the subject-matter of this application, is adapted to 40 be used in association with machine lathes of various types conventionally shown at Fig. 1, having a head 10, tail stock 11, and tool-holder 12. To the head 10 the work 13 is 45 clamped in any usual well-known manner, and the drill or boring implement 14 applied thereto with the tail stock moved up into engagement with the rear end of the drill to receive the point 15.

50 As ordinarily practised, a dog is clamped on the drill 14, and is held manually by the operator to prevent rotation of the drill while the work is rotated. According to the present invention, the dog comprises a sleeve

16 of substantially the usual and ordinary 55 formation, having a set-screw 17 for securing the dog upon the drill. The sleeve 16 has a finger 18 offset therefrom, provided at its extremity with a ball 19. A bar 20 is provided of proper proportions to be 60 clamped into and by the tool-holder 12 of the lathe, and is provided at one end with a socket 21, receiving the ball 19, forming a ball and socket or universal joint, a pin 22 being employed to prevent displacement of 65 the ball 19 from the socket 21.

As a modification, instead of the point 15 engaging directly against the drill, a chuck 23 is provided, having a socket 24 proportioned to receive a drill of substantially the 70 usual and ordinary type, and with a recess similar to the recess described as formed in the drill 14 to receive the point 15.

Instead of employing such chuck 23 and the dog 16, the finger 18 is formed directly 75 upon the body of the chuck, and the ball 19 formed directly upon the finger 18. By this arrangement the bar 20 is attached directly to the ball 19, serving the same purpose of maintaining the drill against rotation ac- 80 complished by the dog 16.

With either embodiment of the invention, the universal joint formed between the drill-retaining member and the bar 20 provides for a difference in altitude of the drill relative to the tool-holder; also provides for variations produced by movements of the tool-holder or the tail stock, or both, in the ordinary use of the device. As ordinarily practised, the manual holding of the lathe 90 dog results in moving the drill from correct alinement, whereby many drills are broken, which is obviated by the use of the device disclosed in this application.

In operation it is obvious that the dog 16, 95 when employed, will be placed upon the drill before the drill is positioned to its work, and after having been properly clamped against the work by the movement of the tail stock, the necessary adjustment with the 100 tool-holder is accomplished. With the use of the embodiment shown at 23, a similar adjustment of the drill is accomplished with the final adjustment of the holding mechanism with and by the use of the tool-holder. 105

What I claim is:

1. A lathe dog comprising a tool-holding sleeve, a bar proportioned for engagement

2
by the tool-holder of the lathe, and a universal joint formed between the tool-holding mechanism and the bar.

2. The combination with a lathe embodying a tool-holder, of a lathe dog embodying a drill-receiving and retaining member, a bar proportioned to be positioned by the tool-holder, and a ball and socket joint formed between the drill-receiving member 10 and the bar.

3. The combination with a lathe embodying a tool-holder, of a member provided with a drill-receiving and retaining recess, an arm formed upon the drill-receiving member, a bar proportioned to be secured to the tool-holder, and a universal joint formed between the bar and the arm.

4. The combination with a lathe embodying a tool-holder, of a lathe dog provided 20 with a drill-receiving and retaining recess, an arm formed upon the drill-receiving member, a ball formed upon the extremity of the arm, a bar proportioned to be retained by the tool-holder and provided with a 25 socket proportioned to receive the ball, and means to prevent the displacement of the ball from the socket.

5. The combination with a lathe embodying a tool-holder, of a lathe dog provided 30 with a drill-receiving recess, means to prevent rotation of the drill within the recess, an arm formed upon the drill-receiving member, a ball formed at the extremity of

the arm, a bar proportioned to be inserted and secured in the tool-holder and provided 35 with a socket proportioned to receive the ball, and means to prevent displacement of the ball from the socket.

6. A lathe dog comprising a drill-receiving sleeve, means to prevent rotation of the 40 drill within the sleeve, a bar, and a ball and socket joint connecting the bar with the sleeve.

7. A lathe dog comprising a drill-receiving sleeve, means to prevent rotation of the 45 drill within the sleeve, an arm formed upon the sleeve and provided at its extremity with a ball, a bar provided with a socket proportioned to receive the ball, and means to prevent displacement of the ball from 50 the socket.

8. The combination with a lathe, of a drill-receiving sleeve, means to prevent rotation of the drill within the sleeve, means to apply feeding stress to the sleeve, a tool- 55 holder-engaging bar, and a ball and socket joint formed between the sleeve and the bar.

In witness whereof, I have hereunto set my hand and seal at Waynesboro, Pennsylvania, this twenty-eighth day of October, 60
A. D. nineteen hundred and nineteen.

CLARENCE G. CASHMAN. [L. s.]
